UNITED STATES PATENT OFFICE.

ABRAHAM PRESS, OF WASHINGTON, DISTRICT OF COLUMBIA.

UNIQUELY RESONANT COIL.

Application filed January 11, 1922. Serial No. 528,581.

To all whom it may concern:

Be it known that I, ABRAHAM PRESS, citizen of the United States, residing at Washington, District of Columbia, have invented 5 certain new and useful Improvements in Uniquely Resonant Coils, of which the following is a specification.

This invention relates to tuning coils such as are used in connection with wireless circuits, or the like, and has special reference to the coupling coils of antennæ.

Heretofore in the art it had been well known that sharpness of tuning could be obtained, to a degree, with the usual 15 forms of constructions of coupling or loading coils or the like. It is a fact nevertheless that where the impressed source of potential included undesired harmonics, that such harmonics, as for example the fifth in an arc 20 set, could not be tuned out or eliminated when merely tuning for the fundamental.

The present invention has for one of its objects the disclosure of a method and means for increasing the sharpness of tuning of 25 loading coils, inductances or the like, for any predetermined frequency. Thus in particular antennæ wherein an adjustable loading or coupling coil is used, with adjustable contactors or the like, it is possible to adjust 30 sharply for the antinodal (or nodal) points normally set up.

Having determined the necessary conditions for the clear manifestation of nodal and antinodal points, it appears that there 35 are innumerable ways of satisfying the above conditions, some of which however are naturally much more practical than the remainder. Manifestly the invention in its broadest aspect includes all manner of additions to 40 well known types of coils, or even changes from the usual constructions. A novel method is also disclosed for arriving at constructions which will satisfy the necessary conditions for sharpness of resonance.

With a view to a better understanding of 45 the principles involved in this invention, the following theoretical development is made part of this specification in which—

Fig. 1 represents the usual type of simple 50 antenna connection.

Fig. 2 corresponds to Fig. 1 and schematically illustrates the stationary wave effects 55 set up in the coupling coil, wherein the antinodal current on the coil merges with the antinodal stationary wave of current on the aerial,

Fig. 3 schematically represents the electrostatic field set up about a coupling coil.

Fig. 4 corresponds to Fig. 3 but illustrates the type of magnetic field set up in the coil. 60

Fig. 5 illustrates a method of determining the self induction distribution along a coil or helix.

Fig. 6 illustrates a modified type of coil 65 shown in Fig. 5.

Fig. 7 illustrates a device for determining the electrostatic distribution about a coil of the type shown in Fig. 5.

Fig. 8 represents a type of uniquely resonant coil contemplated by this invention. 70

Fig. 9 illustrates the method of using an arc generator in connection with a uniquely resonant coil.

Fig. 10 is a modification of Fig. 9.

Fig. 11 shows the use of a uniquely resonant coil in conjunction with an antenna reception circuit. 75

Figs. 12^a and 12^b illustrate the impressed and reflected waves set up along the coil.

Figs. 13^a, 13^b, 13^c illustrate the manner in 80 which dissonance is produced by reflection effects.

Fig. 14 illustrates an end connection device for uniquely resonant coils.

Figs. 15-17 illustrate alternatives to the 85 embodiment illustrated in Fig. 14.

It is to be remembered that the antenna and ground adjustments a_1 , a_2 to a coupling coil secondary b are ordinarily made in such a manner that preferably the maximum amount 90 of antenna current i is indicated in the hot wire instrument or the like A inserted as close to the coupling coil as possible. In view of the fact that the exciting circuit or coil 2 being of an alternating current character, it necessarily follows that it practically determines the position of a nodal point n in the secondary such that on the one side of this point the potential is plus and the other side minus, and vice versa. In stationary wave theory therefore the distribution of potential e and current i must be substantially as indicated in Figure 2. An anti-node of current should therefore occur at n 95 as well as at a_1 and a_2 . On the other hand potential nodes occur at the points just mentioned.

Naturally all such distributions are masked to a great extent by proximity of the earth to the coupling coil, and also due to the fact that to some extent at least progressive waves are set up in the coupling coil, 100 contributing their quota to the aggregate 110

- radiation. The stationary wave theory of a helix with respect to earth has already been given by applicant (see paper on "Wave velocity along coils" in the Electrician, London, June 7, 1918). Professor Fleming had already experimentally determined that the wave velocity along coils did not accord with the velocity of light, but in his particular case was only 1/150th of the same.
- 10 The same sort of slow wave condition applies to the case of a "free helix" or coupling coil raised as far as possible from the electrostatic influence of the earth's surface. The stationary distribution on such free coils has been very effectively demonstrated by Professor J. S. Townsend of Oxford University, in the Journal of the I. E. E., London, for July, 1921. If then a free coil, preferably, can be made to resonate sharply for
- 15 a fundamental frequency, by means of the present invention, it will mean that any parasitic harmonic effect will be eliminated provided the adjustments α_1, α_2 , are made in the first place for such predetermined frequency. In other words, as a distinct feature of the invention resonance or wave coils of a fixed predetermined type for a given single frequency or wave length are to be introduced into the antenna circuit with a
- 20 view to being sharply dissonant for any other disturbing frequency or wave length.
- In order to determine the underlying principle of such uniquely resonant coils it is necessary to consider the differential equations of condition for the more general case, where both the self induction (inductivity) L_x , as well as the capacity C_x , per unit of length are functions, distributedly, of the coil coordinate x measured along the axis, from the geometric center of the coil. It is to be noted (see Figure 3) that the capacity per unit of length C_x for example, for a coil element (annulus) of width dx , will be much smaller for the distance b_2 from the geometric center than for the distance b_1 . Such capacity function C_x is by no means dependent on any frequency magnitude of the impressed E. M. F. but depends wholly on the steady (DC) state potential function $\nabla^2 e = 0$, which Laplacian method is the one in accord with Maxwell's electromagnetic theory. The inductivity function L_x is determined by a similar DC condition. From inspection of Figure 3 it is clear that contrary to the case of the vertical grounded antenna already treated by applicant in the proceedings of the I. E. E. of December 1918, both functions C_x and L_x diminish together in magnitude. Where- 60 as however the electrostatic displacement flux is one-way, both for the interior of the coil as well as in the exterior (see arrows Figure 3), in the case of the magnetic flux the tubes would be in one direction within the coil, but in the opposite direction out-

side the coil (see Figure 4). It is this circumstance that leads to a slightly different treatment for the two fluxes, constructionally in order to meet the necessary conditions for unique resonance.

The differential equations of condition for the most general case is of the form

$$\left. \begin{aligned} L_x \cdot \frac{di}{dt} &= -\frac{de}{dt} \\ C_x \cdot \frac{de}{dt} &= -\frac{di}{dt} \end{aligned} \right\} \quad (1)$$

75

The above general equations have been developed by applicant in the Institute of Radio Engineers paper for November, 1920, when dealing with the Bessel's antenna problem. Separating out the voltage from the current function we have

$$\left. \begin{aligned} \frac{d^2 e}{dx^2} + L_x \cdot \frac{d}{dx} \left(\frac{1}{L_x} \right) \cdot \frac{de}{dx} &= L_x \cdot C_x \cdot \frac{d^2 e}{dt^2} \\ \frac{d^2 i}{dx^2} + C_x \cdot \frac{d}{dx} \left(\frac{1}{C_x} \right) \cdot \frac{di}{dx} &= L_x \cdot C_x \cdot \frac{d^2 i}{dt^2} \end{aligned} \right\} \quad (2)$$

85

90

It is the above type of equations that needs to be solved for the problem at hand.

In view of the fact that both the L_x and C_x diminish together for increasing values of the argument x , applicant conceived the idea of so coordinating the two functions that we have substantially the conditions

$$L_x = \frac{L}{\varphi(x)} \quad (3a)$$

$$C_x = \frac{C}{\varphi(x)} \quad (3b)$$

100

where the L and C are constants, and the function $\varphi(x)$ is the general type of condition which is the crowning feature of the present invention.

To an extent it must be stated that if the antenna coupling (or loading) coils are wound with suitable dielectric material between turns, that then the electrostatic condition (3b) can be made to approximate at least to the condition (3a). It should be borne in mind that the essential condition is rather one of kind than of equal magnitude. Thus it appears that a straight uniform helix wound with suitable insulated wire, or one wound with bare wire upon a dielectric hollow mandrel will approximately meet the above required conditions (3). However, this type of coupling or loading coil construction appears to have been determined previously by Colonel Mauborgne and Captain Hill of the Signal Corps, U. S. Army to give strangely enough, a sharply resonant combination for the usual antenna constructions. However, such prior invention acknowledgment of which is herewith made, had been rather in the nature of experimental than mathematical discovery. Thus the present disclosure though including

110

115

120

125

130

135

the earlier Mauborgne-Hill wave coil as a special case also includes coils and combinations not contemplated by them, since the governing conditions of construction are according to the present invention the simultaneous formulas (3^a) and (3^b) above. Some of the latter types of coil constructions will be gone into further below.

Having conceived the idea of introducing the simultaneous conditions (3^a), (3^b) above, the differential equations (2) take on a simpler form, viz.,

$$15 \quad \frac{d^2e}{dx^2} + \frac{1}{\varphi x} \cdot \frac{d}{dx} \varphi x \cdot \frac{d^2e}{dx} = \frac{LC}{(\varphi x)^2} \cdot \frac{d^2e}{dt^2} \quad (4)$$

with a similar equation in i instead of e .

Now it transpires that the solution of (4), for stationary waves for sustained oscillations of periodicity $1/(2\pi)\cdot p = f$ has been originally determined by applicant to be of a form

$$e = A \cdot \sin f(x) \cdot \sin pt \quad (6)$$

25 where the corresponding function for current would be of the form

$$i = B \cdot \cos f(x) \cdot \cos pt \quad (7)$$

provided no power was given to the line for radiation. However, should radiation take place the time lag would be of an amount which latter should differ from 90° . The above equations (5) and (6) are in complete accord with the physical findings of Professor Townsend above mentioned, showing that no departure is called for from the standard Maxwellian methods for the determination of the line constants L_x and C_x whether for long or short waves. The necessary and sufficient condition for determining the unknown function $f(x)$ will be found to be

$$30 \quad \frac{d}{dx} f x = \frac{1}{\varphi x} \quad (8)$$

45 so that if $\varphi(x)$ is known $f(x)$ and the solutions (6) and (7) are known for any particular case. It should be added that the solutions (6) and (7) require that we have

$$50 \quad LC p^2 = 1$$

$$whence f = \frac{1}{2\pi\sqrt{LC}} \quad (9)$$

55 It is the above condition (9) coupled with the two equations of condition (3^a), (3^b) that establish the importance of the principle underlying the present invention. That is to say, provided the distributed capacity per unit of length C_x is so coordinated with respect to the self induction L_x that

$$\frac{C_x}{L_x} = \frac{C}{L} = \text{constant} \quad (10)$$

65 throughout the coil then will it be found

that the coil is uniquely resonant to the frequency f given by equation (9). For any other frequency the coil will actually be dissonant. The problem then is, so to arrange the elements of the coil that the proportionality (10) obtains substantially throughout.

In order to carry out the above condition the following method can be employed:— An arbitrary helix devoid of insulation such as the curved helix (Figure 5) is first excited with a definite amount of current by means of a DC source B by means of a switch S and then explored by means of an exploring loop EL connected to a ballistic galvanometer G. In this way the self induction function

$$L_x = \frac{L}{\varphi(x)}$$

can be determined.

If now a template made up of four sections 5, 5, 6, 6, is made up to practically simulate the cross section of the coil, with the one portion 5, 5 connected together by means of suitable leads 5', 5' and 6', 6' to a suitable source of low tension alternating current A. C. it is possible to map out the lines of electrostatic flux both within and without the coil. This is accomplished in the following manner. The template is immersed in a flat dish D in which latter is placed some electrolyte such as dilute sulphuric acid. Then by a point by point method the flux lines of alternating current flow can be suitably mapped by means of a telephone t. Thus to determine the point along the flux line curve corresponding to the point p, an exploring needle 7' similar to that of 7 placed at the point p, is used. It will be found that only at a point such as p₃ as against the points p₁ and p₂ will the maximum sound be heard in the telephone. In this manner having determined the tubes of flux, a graded type of dielectric for the individual tubes mapped out can be made use of in order to give the requisite amount of electrostatic displacement for the elements Δx (approximations to dx) so that the function

$$110 \quad C_x = \frac{C}{\varphi(x)}$$

is obtained. Instead of the coil (Figure 5) for example, a coil such as (Figure 6) could be used. Obviously the distinction between the above more nearly theoretical coil, according to the present theory, and the Mauborgne-Hill straight cylindrical wave coil is that insulation is preferably employed both outside and within the coil.

On the other hand, instead of employing an electrostatic correction alone, a combined magnetic method can be employed. Thus two shields (curved or otherwise) of

70

75

95

100

105

110

115

120

125

130

magnetic material (powdered if desired) can be employed, in order to limit both the electrostatic induction lines as well as those of magnetic induction. In the case of high frequency currents, clearly the shields internal and external, may be split tubes (curved or otherwise) of sheet metal such as copper. Then in view of eddy current shielding the magnetic flux will not be able to penetrate the copper to any great extent provided very high frequency currents are employed.

Such a type of coil is indicated in Figure 8, where the coil has placed within it a suitably shaped inner shield, in the diagram flared inwardly toward the ends, and an external split shield 9 in the diagram flared outwardly toward the ends. The spacings

$$\begin{aligned} (1) \quad \cos [\phi(x) - pt] &= \cos \phi x \cdot \cos pt + \sin \phi x \cdot \sin pt \\ (2) \quad \cos [\phi(x) + pt] &= \cos \phi x \cdot \cos pt - \sin \phi x \cdot \sin pt \end{aligned} \quad \{ \quad (11)$$

When the two waves meet in proper phase relationship we have by superposition

$$\cos (\phi x - pt) + \cos (\phi x + pt) = 2 \cdot \cos \phi x \cdot \cos pt \quad (12)$$

It is the right hand term which represents the resultant stationary wave. Thus it is important to avoid disturbing dead ends.

Should it transpire that the end of the coil does not exactly correspond to an antinodal point as is indicated in Figure 12^a (condition $m = \frac{1}{2}$ where λ equals the wave length) we will have instead of a reflected wave such as that indicated in Figure 12^b, a reflected wave as indicated in Figure 13^b, which latter condition tends to set up a further wave 13^c which latter by the time it reaches the end of the coil may be progressively out of phase with the original wave Figure 13^a, and thus set up a complexity of waves tending to produce dissonance which dissonance will be most complete when m is an incommensurable part of unity.

To bring out this feature, in the case of uniquely resonant coils, we note that the function

$$y = \Sigma \frac{1}{n^2} \cdot \sin n f(x) \quad (13)$$

is likewise a possible solution for equations (2). The plurality of stationary waves indicated by (13) having different internodal spaces will therefore tend to produce a blurring effect depending on the number of terms included under the sign Σ .

Thus it follows that the value of m is a very important matter and it suggests therefore, as a decided feature of this invention, that it is preferable to arrange an adjustable spire mechanism such as that indicated, in Figure 14, for example. It will be seen that the end spires e_8, e'_8 comprise in one

of the one shield from the other can be so proportioned as to satisfy the required condition (10) above. Be it observed that by means of reticulated shields the function $\phi(x)$ can indeed be made to accord only for frequencies substantially above a predetermined amount when the skin effect begins to count for the higher frequencies.

The conditions tending to set up dissonance are very important, and lead to constructions serving to produce sharper resonance than has heretofore been possible. In so far as stationary waves can be conceived as set up by oppositely directed progressive waves, one of which is the impressed forward wave and the other the opposed reflected wave from the end of the coil, we have the following:

embodiment curved tubing which can be slipped over the free ends of the coil 1 for adjusting purposes. Still another method can be employed comprising the use of contacting strip instead of tubing. A still further method can be employed which comprises the use of reticulated material or caps e_8, e'_8 covering the ends of the coils, which caps may or may not be connected to earth, and aerial of the antenna system. It should be pointed out however that it is not necessary to have both ends capped to obtain the desired result, nor is it necessary to provide the shielding arrangement at the ends of the coil. Thus an adjustable sliding sleeve of a split type can be employed about the center of the coil as indicated in Figure 16. An equivalent method is indicated in Figure 17 where the two helices are provided with an adjustable central sliding or capacitance connection or the like.

I claim—

1. In combination with a source of alternating electromotive force, an open ended helix comprising a shielding means, said shielding means extending substantially a half stationary wave length of said helix for the frequency of said electromotive force.

2. An open ended helix comprising a conductive shielding means internal and external to said helix.

3. A method of making up uniquely resonant coils, comprising the step of determining the coefficient of self induction distribution, and then modifying the coefficient of capacity distribution, to give a substan-

- tially linear relationship between said coefficients.
4. In combination with an antenna, an arc source of electro-motive force, a uniquely resonant coupling coil, and means for eliminating the arc harmonics by adjusting said coupling coil for the uniquely resonant wave length corresponding to the fundamental of said arc source.
5. In combination with an electric source of high frequency, a helix, means for producing a uniquely resonant characteristic in said helix, said means comprising a device for adjusting the phase of the reflected waves to produce stationary waves on said helix.

6. In combination with an open ended helix, means for positioning the reflecting open end effects of said helix.
7. An open ended helix comprising in combination, an adjustable means for varying the end spire length of said helix.
8. A uniquely resonant helix, comprising in combination, means for adjusting the effective end spire length of said helix.

9. A uniquely resonant coil comprising in combination a means for adjusting the effective dead end spire length of said coil.

In testimony whereof I have affixed my signature.

ABRAHAM PRESS.
